(57) **CLAIM**

The ornamental design for a stand for vacuum cleaner as shown and described.

DESCRIPTION

1. Stand for vacuum cleaner
  2. Stand for vacuum cleaner
- FIG. 1.1 is a perspective view of a stand for vacuum cleaner according to a first embodiment of the present design; FIG. 1.2 is a front view thereof; FIG. 1.3 is a rear view thereof; FIG. 1.4 is a left side view thereof; FIG. 1.5 is a right side view thereof; FIG. 1.6 is a top view thereof; FIG. 1.7 is a bottom view thereof; FIG. 2.1 is a perspective view of a stand for vacuum cleaner according to a second embodiment of the present design; FIG. 2.2 is a front view thereof; FIG. 2.3 is a rear view thereof; FIG. 2.4 is a left side view thereof; FIG. 2.5 is a right side view thereof; FIG. 2.6 is a top view thereof; and FIG. 2.7 is a bottom view thereof.

(Continued)

The broken lines illustrate portions of the stand for vacuum cleaner that form no part of the claimed design.
